DESIGN FOR A CONTAINER

Isaac Strouse, Baltimore, Md., assignor to Liberty
Distilleries, Inc., Baltimore, Md.

Application May 8, 1934, Serial No. 51,723

Term of patent 7 years

To all whom it may concern:

Be it known that I, ISAAC STROUSE, a citizen of the United States, residing at Baltimore, Maryland, have invented a new, original, and ornamental Design for Containers, of which the following is a specification, reference being had to the accompanying drawing, forming part thereof.

Fig. 1 is a perspective view of the container, looking at the front thereof,

Fig. 2 is a side view of the container,
Fig. 3 is a top view of the container.

The front and back faces are identical, and the two sides are identical.

I claim:

The ornamental design for a container, as shown and described.

ISAAC STROUSE.
